US00D947024S

(12) **United States Design Patent** (10) **Patent No.:** **US D947,024 S**
(45) **Date of Patent:** **** Mar. 29, 2022**

(54) **PACKAGING**

(71) Applicant: **Apple Inc.**, Cupertino, CA (US)

(72) Inventors: **Evan Cernokus**, Campbell, CA (US);
Mark T. Uyeda, Campbell, CA (US)

(73) Assignee: **Apple Inc.**, Cupertino, CA (US)

(**) Term: **15 Years**

(21) Appl. No.: **29/807,541**

(22) Filed: **Sep. 13, 2021**

Related U.S. Application Data

(63) Continuation of application No. 29/758,348, filed on Nov. 13, 2020, now Pat. No. Des. 930,477, which is a continuation of application No. 29/734,868, filed on May 15, 2020, now Pat. No. Des. 902,032, which is a continuation of application No. 29/706,854, filed on Sep. 24, 2019, now Pat. No. Des. 884,470, which is a continuation of application No. 29/618,870, filed on Sep. 25, 2017, now Pat. No. Des. 861,497, which is a continuation of application No. 29/598,108, filed on Mar. 23, 2017, now Pat. No. Des. 806,537, which is a continuation of application No. 29/523,465, filed on Apr. 9, 2015, now Pat. No. Des. 789,800.

(57) **CLAIM**

The ornamental design for packaging, as shown and described.

DESCRIPTION

FIG. 1 is a bottom front perspective view of packaging showing the claimed design;

FIG. 2 is a bottom view thereof;

FIG. 3 is a top view thereof;

FIG. 4 is a left side view thereof;

FIG. 5 is a right side view thereof;

FIG. 6 is a front view thereof; and,

FIG. 7 is a rear view thereof.

The broken lines in the figures show portions of the packaging that form no part of the claimed design.

1 Claim, 5 Drawing Sheets
